TUNABLE INDUCTANCE

Raymond J. Cary, Jr., Long Beach, Calif., assignor to the United States of America as represented by the Secretary of War

Application January 29, 1946. Serial No. 644,173

1 Claim. (Cl. 171—242)

1 This invention relates to electrical apparatus and more particularly to improvements in tunable inductances.

The conventional tuned-circuit inductance for high frequency amplifier circuits is a helical coil. The inductance of this coil may be either fixed or variable. The variable inductance coil usually has a hollow core in which a plug of magnetic material (e. g., polyiron) or non-magnetic material (e. g., brass) may be moved to vary the inductance of the coil.

At very high radio frequencies, the distributed capacity and the capacity to ground of this conventional coil, which together with other stray tube and wiring capacities determine the stray shunt capacitance, may be of sufficient magnitude to seriously affect the gain-bandwidth factor of the circuit. To obtain the maximum gain-bandwidth factor, the distributed capacity of the coil and its capacity to ground must be made as small as possible.

An object of the present invention is to provide a tunable inductance for use with high frequency amplifier circuits in which the shunt capacity to ground is minimized.

A further object of the invention is to provide such a tunable inductance with a minimum distributed capacity.

A still further object is to provide such a tunable inductance with a readily-adjustable stable tuning control.

Other objects and advantages of the invention will be apparent during the course of the following description.

Essentially the present invention is a mechanism for axially expanding or contracting a helical coil thereby varying its inductance. The coil is wound about a dielectric rod and one end of the coil is rigidly affixed to the dielectric rod. The dielectric rod moves axially within a tubular mount which is rigidly affixed to the amplifier chassis. The other end of the coil is maintained fixed with respect to the chassis. Hence, axial motion of the dielectric rod within the tubular mount will expand or contract the coil axially, and consequently will vary its inductance.

In the accompanying drawing forming a part of this specification, the single figure is a cross-sectional view illustrating one embodiment of the invention.

In the figure, numeral 10 designates a dielectric rod having an external shoulder near one end. While the material of rod 10 is a dielectric in the present embodiment, other materials may be used, under different requirements. The rod

2 10 is disposed within a metallic tubular mount 11. One end of the tubular mount 11 has an external thread 12 whereby the mount may be secured to a chassis 13. The other end of tubular mount 11 has an internal thread 14. The tubular mount 11 has an internal shoulder beyond the internal thread 14.

A section of rod 10 extends externally beyond tubular mount 11. A helical coil 15 is disposed about this external section of rod 10. One end of coil 15 is rigidly affixed to a pin 16 which extends through the end of rod 10. The other end of coil 15 is fixed to a tie-point pin 17. The pin 17 is swaged to a protrusion on an insulating block 18. Insulating block 18 is maintained in a fixed position with respect to the chassis 13 by means of a screw 19. Hence, it is obvious that the end of coil 15 which is attached to pin 17 will be maintained in a fixed position with respect to chassis 13 and tubular mount 11. The tie-point pin 17 is here shown as insulated from chassis 13 by means of the insulating block 18. Pin 17 could of course be grounded directly to chassis 13 if desired.

Axial motion of rod 10 with respect to tubular mount 11 is effected by an adjusting screw 20 moving within thread 14 and applying pressure to one end of rod 10. The pressure between rod 10 and screw 20 is maintained by a spring 21 which is disposed about rod 10 and between the external shoulder of rod 10 and the internal shoulder of tubular mount 11.

The inductance of coil 15 may be varied by adjusting the screw 20. One end of coil 15 is maintained fixed by pin 17 and therefore axial motion of rod 10 caused by rotation of the adjusting screw 20 will either expand or contract coil 15, thereby changing the axial spacing or pitch of coil 15 and consequently its inductance.

The rod 10 accurately follows the motion of the screw 20 because of the pressure of the spring 21. The pressure of spring 21 also serves to prevent vibration along the axis of the coil, which vibration if present would vary the inductance of the coil introducing a vibration modulation in the output circuit.

The invention results in having the coil 15 characterized by a low distributed capacity and by a low shunt capacity to ground. The coil 15 may be sufficiently removed from the chassis 13 to minimize shunt capacity to ground. The possibility of widely spacing the turns on coil 15 in conjunction with the use of the dielectric rod 10 tends to minimize the distributed capacity of coil 15.

It will be apparent that there may be deviations from the invention as described which still fall fairly within the spirit and scope of the invention.

What is claimed is:

A tunable inductance including a tubular mount having an internal thread at one end thereof, a dielectric rod disposed partly within said tubular body portion and extending externally beyond said tubular mount at the other end thereof, screw means associated with said internal thread and adapted to apply pressure to the end of said rod which is disposed within said tubular mount, spring means disposed about said rod and adapted to maintain the pressure between said rod and said screw means, a helical coil of conducting material disposed about the external portion of said dielectric rod, one end of said coil being rigidly affixed to said dielectric rod and the other end fixed with respect to said tubular mount, whereby the motion of said screw

means within said internal thread will move said dielectric rod axially with respect to said mount thereby varying the pitch of said helical coil and changing the inductance thereof.
